UNITED STATES PATENT OFFICE.

HENRY H. COLLINS, JR., OF PHILADELPHIA, PENNSYLVANIA.

DESIGN FOR A CARD-MOUNT.

No. 37,861:

Specification for Design.

Patented Feb. 27, 1906.

Application filed January 19, 1906. Serial No. 296,914. Term of patent 3½ years.

To all whom it may concern:

Be it known that I, HENRY H. COLLINS, Jr., a citizen of the United States, and a resident of Philadelphia, Pennsylvania, have invented a certain new, original, and ornamental Design for a Card-Mount, of which the following is a specification, reference being had to the accompanying drawing, forming part thereof.

I claim—
The ornamental design for a card-mount, as shown.

HENRY H. COLLINS, JR.
